UNITED STATES PATENT OFFICE.

JOSE TOPACIO Y GONZALES, OF MANILA, PHILIPPINE ISLANDS.

COMBINED TELEGRAM BLANK, ENVELOPE, AND DELIVERY SHEET.

Application filed June 15, 1926. Serial No. 116,136.

This invention relates to blanks for telegrams received for delivery, envelopes in which the telegrams or messages are delivered to the addressees, and delivery sheets on which records of the delivery of the messages are kept.

The invention has for one of its objects to reduce to the minimum the time and work involved in typewriting and otherwise preparing the messages for delivery to the addressees, and to attain this end I provide a combined telegram blank, envelope and delivery sheet, the same consisting of a single sheet of paper on which the message and the name and address of the person to whom it is to be delivered may be readily handwritten or typewritten and which may be readily folded to conceal the message and expose the name and address.

10 A further object of the invention is the provision of an article of the character stated wherein the delivery sheet, which is to be signed by the person receiving the telegram, can be readily detached without unsealing and unfolding that portion of the article on which the message is typewritten.

15 The invention is hereinafter fully described and claimed, and illustrated in the accompanying drawings, wherein:

20 Figure 1 is a plan view of a combined telegram blank, envelope and delivery sheet embodying my invention.

25 Figure 2 is a similar view looking at the opposite side of the article.

30 Figure 3 is a plan view of the article after portions thereof have been removed preparatory to folding and sealing the same.

35 Figure 4 is a plan view of the partly folded article,

40 Figure 5 is a plan view of the completely folded article,

45 Figure 6 is a plan view of the folded article after the removal therefrom of the delivery sheet,

50 Figure 7 is a sectional view taken on the plane indicated by the line 7-7 of Figure 5,

55 Figure 8 is a similar view taken on the plane indicated by the line 8-8 of Figure 5, and

60 Figure 9 is a plan view of the article after removing therefrom the delivery sheet and breaking away the sealing flap.

Corresponding and like parts are referred to in the following description, and designated in the several views of the accom-

panying drawings, by similar reference characters.

The article consists of a single sheet of paper, the portion 1 of which constitutes the telegram blank, the portion 2 the delivery sheet, the portion 3 the sealing flap for the folded article, and the portions 4 and 5 forms employed for the purpose of keeping records of efforts made to effect the delivery of undelivered messages. The telegram blank 1 and delivery sheet 2 are arranged one above the other and separated by a weakened or tear line 6. The sealing flap 3 extends from a lateral edge of the telegram blank 1 and is located adjacent the upper edge thereof. These parts are integral and not separated by a weakened or tear line. The portion 4 is connected to the telegram blank 1 and sealing flap 3 and is separated from these parts by weakened or tear lines 7 and 8. The portion 5 is connected to the delivery sheet 2 and sealing flap 3, and is separated from these parts by weakened or tear lines 9 and 10.

The portions 4 and 5 are used only in the event that it is found impossible to deliver the message, and as suggested in Figure 2 contain the usual printed matter and blank spaces. The delivery sheet is employed to preserve a record of the delivery of the message and contains as suggested in Figure 2 the usual printed matter and blank spaces. The telegram blank 1 also contains the usual printed matter, and the body of the message is to be written in the space 1^a thereof and the name and address of the person to whom the message is to be delivered is to be written in the space 1^b. The sealing flap 3 and the delivery sheet 2 are so arranged with respect to the space 1^b that by folding them in rear of said space and by the use of a transfer sheet the name and address may be simultaneously written on both.

The record forms 4 and 5 should be detached before the name, address and message are written on the telegram blank 1 and sealing flap 3. After the removal of these forms, the article appears as shown in Figure 3. To prepare the telegram for delivery, the telegram blank 1 is first folded transversely along the line indicated by the marks 12 and then transversely along the line 13. The article now appears as shown in Figure 4. The folded telegram blank 1 and the delivery sheet 2 are then folded longitudinally

along the line 14, and the sealing flap 3 is thence folded longitudinally along the line indicated by the marks 7 over the folded telegram blank 1 and its free or outer end 5 adhered to said blank. The article now appears as shown in Figure 5 with the message completely hidden and the name and address of the person to whom the telegram is to be delivered on the outer side of the 10 sealing flap and delivery sheet. The entire article is delivered to the person who, after signing for the same on the line 15, detaches the delivery sheet 2 and hands it to the messenger who in turn delivers it to the proper 15 person at the telegraph office. The telegram may be readily opened by inserting a finger beneath the sealing flap 3 and breaking it away along the line 7. To permit of its being retained in folded condition, the article 20 is provided with adhesive at the points indicated by the reference characters 1^c, 1^a and 3^a in Figures 1 and 9.

It should be understood that the drawings 25 are merely illustrative and do not pretend to give exact proportions. Furthermore, the said drawings are illustrative of a preferred

construction, it being my expectation that various changes and modifications may be made without departing from the spirit and scope of my invention.

30

What is claimed is:

An article of the character set forth consisting of a single sheet of paper and embodying a telegram blank adapted to be folded to conceal the message, a delivery sheet connected to the telegram blank and adapted to extend beyond the telegram blank when the same is folded, the telegram blank and delivery sheet being arranged one above the other and detachably connected, a sealing flap extending from the telegram blank, a record form connected to the telegram blank and sealing flap, and a second record form connected to the delivery sheet and sealing flap, the record forms being detachably connected to the other parts to permit them to be removed and retained as records and to free the sealing flap and permit the sealing flap to be folded over and secured to the telegram blank when the blank is folded.
